UNITED STATES PATENT OFFICE.

WILLIAM HADDEN, OF BROOKLYN, NEW YORK.

RAILWAY-SIGNALING APPARATUS.

SPECIFICATION forming part of Letters Patent No. 315,772, dated April 14, 1885.

Application filed June 12, 1884. (No model.)

To all whom it may concern:

Be it known that I, WILLIAM HADDEN, of Brooklyn, in the county of Kings and State of New York, have invented a new and useful Improvement in Railway-Signaling Apparatus; and I do hereby declare that the following is a full, clear, and exact description thereof, reference being had to the accompanying drawing, forming a part of this specification.

10 The object of my invention is to provide a railway-signaling apparatus which may be operated at any point in the length of a track-section by the entrance of a train upon the said track-section or its emergence therefrom, the signal to be either audible or visible.

15 My invention consists in two oppositely-arranged pairs of track circuit-closing instruments placed at the opposite ends of the track-section to be protected and in a polarized relay placed between the track-instruments and capable of being operated thereby, the said relay controlling a local circuit in which is placed an electric gong or an electrically-operated banner or colored light.

20 The track A, which is of ordinary construction, is provided with two pairs of oppositely-arranged circuit-closing track-instruments, B C and B' C', the circuit-closing instruments B C being located at one end of the track-section to be protected, and the circuit-closing instruments B' C' at the opposite end of the track-section. These circuit-closing track-instruments may be of any approved construction and may be connected with and operated by the track in the usual way.

25 At any desired point between the ends of the section to be protected is located a polarized relay, D, whose coils *a a'* are connected by wires with one pole of the battery E. The remaining terminal of the coil *a* is connected by a wire, *b*, with the contact-point of the circuit-closing track-instrument C, and by a wire, *b'*, with the contact-point of the circuit-closing track-instrument C'. The remaining terminal of the coil *a'* is connected by a wire, *c*, with the contact-point of the circuit-closing track-instrument B', and is also connected by a wire, *c'*, with the contact-point of the circuit-closing track-instrument B. The levers of the circuit-closing track-instruments B C are connected by wires *e e'* with the ground G, and the levers

of the circuit-closing track-instruments B' C' are connected by wires *f f'* with the ground G, and the remaining pole of the battery E is also connected with the ground G. The polarized armature-lever D', located between the pole of the magnet of the relay D, carries a point, *g*, which is capable of being brought into contact with the point *h*. The armature-lever D' is in a local circuit consisting of the wire *i*, electric gong or signaling apparatus *j*, battery *k*, and wire *l*. When a train enters upon section A in the direction indicated by the arrow, it closes both circuit-closing track-instruments B C, the track-instrument B being closed before 65 the track-instrument C producing no effect on account of the current being directed through the coil *a'*, so as not to change the polarity of its core or pole extension, and the track-instrument C remaining closed for an instant after 70 the opening of the track-instrument B allows the current to pass from the battery E through the coil *a*, wire *b*, and contact-point and lever of the circuit-closing instrument C, the wire *e'* to the ground, the current passing through 75 the coil *a* in the direction required to produce in the core and pole extension of the said coil an increase of magnetism, causing the armature D to be attracted by the said pole, completing the local circuit between the contact-point *g*, carried by the said lever and the contact-point *h*. The current then flowing through the signaling-gong *j* or through other signaling apparatus that may be substituted for it, continues to sound the alarm or to give a visible signal so long as the armature-lever D' is 80 undisturbed; but when the train passes off from the section A it closes the circuit-closing instruments C' B', but holds the instrument B' closed a short time after the instrument C' is 85 opened. The current then flows from battery E through the coil *a'* of the relay D, through the wire *c*, and the contact-point and lever of the track-instrument B', through the wire *f*, to the ground, drawing the armature-lever D' toward the pole of the coil *a'*; and breaking the contact between the contact-point *g* and the contact-point *h*, stopping the operation of the signaling-gong *j*, or other signaling apparatus placed at that point or throwing the signal to 90 "safety." When the train enters the opposite end of the section to be protected, the reverse 95

- of what has been described occurs. The train passes over the track-instrument B' without producing any effect, but in passing over track-instrument C' it causes current of the 5 battery E to flow through the coil a of the magnet D, through the wire b', to the contact-point and the lever of the track-instrument C', and through the wire f', to the ground. The armature-lever D' is now drawn toward the pole 10 of the coil a, and the contact between the point g carried by the armature-lever and the fixed contact-point h is completed, causing the current of the local circuit to flow through the magnets of the gong j, and giving the alarm, 15 until the train, in passing off the opposite end of the section, closes the track-instrument B, directing the current from battery E through the coil a' of the magnet D, the wire c', and contact-point and lever of the track-instrument 20 B, wire e to the ground, when the armature is drawn toward the pole of the coil a', and the local circuit is broken and the alarm-signal ceases; or if a visible signal is used it is put to "safety." The attraction of the armature 25 D' for the poles of the coil a' causes the said armature to remain in either of the two positions in which it is drawn by the attraction of the said poles, so that if the local circuit is closed by one of the track-instruments it will 30 remain closed without the current passing through the main circuit until the armature-lever D' is again operated by the impulse sent through the main circuit by closing one of the track-instruments. 35 My invention is especially designed for rail-way-bridges and short sections of track to be protected, and will protect a section without regard to the direction in which the train is moving. 40 The polarized relay shown in connection

with my improved signaling apparatus is of the kind known as the "Siemens' polarized relay," but any relay suited to the purpose may be used.

I claim—

1. In electric railway-signaling apparatus, 45 two pairs of circuit-closing track-instruments, B C and C' B', located at opposite ends of the track-section to be protected and oppositely arranged with respect to each other, the inner track-instruments of both pairs being connected with one terminal of the same coil of the polarized relay D, and the outer track-instruments of both pairs being connected with one terminal of the other coil of said relay, in 50 combination with the said polarized relay D and a local circuit adapted to operate a visible or audible signal, substantially as herein shown and described.

2. In electric railway-signaling apparatus, 55 a polarized relay, D, adapted to maintain either an open or closed local circuit by the bias of the poles, and two pairs of oppositely-arranged circuit-closing track-instruments, B-C and C' B', and circuits connected with the said track-instruments which are capable of reversing the current in the polarized relay D when a train enters and emerges from the section protected by the signaling apparatus, substantially as 60 specified.

3. The combination, with the polarized relay D, of the battery E and its ground and line connections, the track-instruments B C B' C', the wires b b' c c', and ground-wires e e' f f', as specified.

WILLIAM HADDEN.
